P. J. McELROY,
SYRINGE,
APPLICATION FILED APR. 12, 1915.

1,165,686.

Patented Dec. 28, 1915.

Inventor:
P. J. McELROY

By Right Honorable Linley May
Attorneys

UNITED STATES PATENT OFFICE.

PATRICK J. McELROY, OF CAMBRIDGE, MASSACHUSETTS, ASSIGNOR OF ONE-HALF TO
CHARLES F. BLINN, JR., OF BOSTON, MASSACHUSETTS, AND RENTON WHIDDEN, OF
BROOKLINE, MASSACHUSETTS, RECEIVERS OF RANDALL FAICHNEY CO.

SYRINGE.

1,165,686.

Specification of Letters Patent. Patented Dec. 28, 1915.

Application filed April 12, 1915. Serial No. 20,622.

To all whom it may concern:

Be it known that I, PATRICK J. McELROY, a citizen of the United States, and a resident of Cambridge, in the county of 5 Middlesex and State of Massachusetts, have invented certain new and useful Improvements in Syringes, of which the following is a specification.

This invention relates particularly to 10 small syringes for hypodermic use, comprising a barrel or container usually of glass having a contracted outlet at one end adapted to engage a hypodermic needle, its other end being open, and a piston comprising 15 an elongated cylindrical stem of smaller diameter than the interior of the barrel, and compressible material engaged with the inner end of the stem and constituting a compressible head which conforms closely to 20 and is in sliding contact with the internal surface of the barrel or container.

The invention has for its object to provide certain improvements in the form and construction of the inner end portion of 25 the stem and of the compressible head engaged therewith, whereby the head may be readily and securely engaged with the stem and caused to turn therewith in the barrel.

The invention consists in the improvements which I will now proceed to describe 30 and claim.

Of the accompanying drawings forming a part of this specification: Figure 1 is a side elevation of the stem, and a longitudinal section of the head, of a piston embodying my invention, the barrel being shown in section; Fig. 2 represents a side view of a portion of the stem; Fig. 3 represents an end view showing the inner end face of 40 the stem; Fig. 4 represents a sectional view of the head, detached and contracted to substantially its normal size; Figs. 5, 6, and 7 represent views corresponding respectively to Figs. 2, 3 and 4, and illustrating 45 a modification.

The same reference characters indicate the same or similar parts in all the views.

In the drawings, 12 represents the stem and 13 the head of a syringe piston, said 50 stem and head being movable in a syringe barrel or container 14.

The stem may be made of glass or any other suitable material and may be of metal, if desired. The stem is of cylindrical form

and its inner end is formed substantially at 55 right angles with its longitudinal axis, and constitutes what I call an inner end face 15. The diameter of the stem is reduced to form an annular shoulder 16, separated from the end face 15 by a narrow peripheral 60 portion 17, and facing oppositely from the end face 15.

The reduced portion 12^a of the stem is adapted to be embraced by the sleeve herein-after described, and therefore constitutes a 65 sleeve-engaging portion.

The head 13 may be made of any suitable compressible material such as asbestos, and formed from an asbestos cord wound and disposed on the stem substantially according to the disclosure in my Patents 919,918 and 962,657 to cover the end face 15, the peripheral portion 17 and form a sleeve portion engaging the shoulder 16. I prefer, however, to mold the head from elastic rubber or its equivalent, said head being elastically yielding and compressible. The head includes a body portion 13^a extending across and covering the end face 15, and an annular marginal portion 13^b surrounding the peripheral portion 17 of the stem and compressed between the said portion and the interior of the barrel. 70 75 80

On the marginal portion 13^b is formed a sleeve 18 which is internally contracted to 85 embrace the stem portion 12^a and form an internal shoulder 19, adapted to engage the stem shoulder 16. The head and sleeve constitute a cup adapted to receive the end face 15 and the adjacent portions of the 90 stem, as shown by Fig. 1, the body portion 13^a of the head covering the end face 15, and being held against said face by the engagement of the internal shoulder 19 with the stem shoulder 16, the stem and head being 95 thus connected for simultaneous longitudinal movement.

Sometimes a sticky liquid is administered by a syringe of this character, in which case the head, which conforms closely to, and is 100 compressed by the internal surface of the barrel, becomes cemented more or less firmly to the barrel by said liquid, after protracted disuse of the syringe while it contains the liquid, so that considerable force is required 105 to free the head and permit it to slide in the barrel. The easiest and best way of freeing the head is by turning it in the barrel, by

turning the stem. If endwise pressure is exerted on the stem to free the head, the pressure is liable to break the barrel. To prevent the stem from turning in the head 5 without turning the latter, and to insure the rotation of the head by the stem without liability of injuring the marginal portion 13^b by the twisting strain exerted on the head by the stem, I provide the end face 15 with 10 spurs 21, formed to indent the inner surface of the body portion 13^a, and thus cause said body portion and the marginal portion to turn with the stem. Said spurs are preferably pointed and of pyramidal form al- 15 though they may be of conical or other form, if desired. The peripheral portion 17 is preferably provided with similar spurs 22 radiating therefrom and formed to indent the inner surface of the marginal portion 13^b 20 of the head. The spurs 22, however, un- aided by the end face spurs 21, cannot be relied upon to free the head, because they are liable to turn in the marginal portion of the head, without turning the head. I have 25 found that the end face spurs 21, either alone or in coöperation with the peripheral spurs 22, constitute a satisfactory and effective means for causing the head to turn with the stem without injurious twisting strain. 30 The reduced portion 12^a of the stem adjacent to the shoulder 16, is also preferably pro- vided with spurs 24 formed to indent the inner surface of the sleeve 18 and aid in causing the head to turn as a whole with 35 the stem.

Figs. 5, 6 and 7 illustrate a modification in which the sleeve portion 18^a of the head is relatively short, and is provided with an internal annular shoulder 19^a adapted to engage a shoulder 16^a on the stem, the peripheral spurs 22 and 24 being omitted. The stem may be provided with transverse ori- 40 fices 27 to receive stitches attaching the head to the stem, said orifices being indicated by dotted lines in Figs. 5 and 6.

I claim:

1. A syringe piston comprising a stem having an end face at its inner end, spurs projecting outwardly from said end face, 50 head-engaging means adjacent to said face, and a sleeve-engaging portion adjacent to said head-engaging means, and an elastic head including a body portion covering said face, a marginal portion embracing a por- 55 tion of the periphery of the stem and a sleeve

embracing said sleeve engaging portion, whereby the body portion of the head is held in engagement with said spurs, to cause the head to turn with the stem.

2. A syringe piston comprising a stem 60 having an end face at its inner end, spurs projecting outwardly from said end face, head-engaging means adjacent to said face, and a sleeve-engaging portion adjacent to 65 said head-engaging means, and an elastic head including a body portion covering said face, a marginal portion embracing a portion of the periphery of the stem and a sleeve embracing said sleeve engaging portion, whereby the body portion of the head is held 70 in engagement with said spurs, to cause the head to turn with the stem, the stem being provided also with peripheral spurs engag- 75 ing the internal surface of the marginal por- tion of the head.

3. A syringe piston comprising a stem having an end face at its inner end, spurs projecting outwardly from said end face, head-engaging means adjacent to said face, and a sleeve-engaging portion adjacent to 80 said head-engaging means, and an elastic head including a body portion covering said face, a marginal portion embracing a portion of the periphery of the stem and a sleeve embracing said sleeve engaging portion, 85 whereby the body portion of the head is held in engagement with said spurs, to cause the head to turn with the stem, the stem being provided also with peripheral spurs engag- 90 ing the internal surface of the marginal portion of the head, and with other pe- 95 ripheral spurs engaging the internal surface of said sleeve.

4. A syringe piston stem having an end face at its inner end, head-engaging spurs 95 projecting outwardly from said end face and complemental head-engaging means adjacent to said face, and adapted to hold a com- 100 pressible head against said spurs.

5. A syringe piston stem having an end 100 face at its inner end, head-engaging spurs projecting outwardly from said end face and complemental head-engaging means adjacent to said face, and adapted to hold a com- 105 pressible head against said spurs, said stem being also provided with radial spurs to en- gage other parts of said compressible head.

In testimony whereof I have affixed my signature.

PATRICK J. McELROY.
